UNITED STATES PATENT OFFICE

FRED E. WEICK, OF Langley Field, Hampton, Virginia

PROPELLER

Application filed February 6, 1929. Serial No. 337,978.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to propellers and more particularly to a type of propeller for use on aircraft.

10 The primary object of this invention is to provide an aerodynamically efficient metal propeller which will be relatively light in weight and which will lend itself to easy manufacture and low manufacturing costs on a production basis.

15 Another object of this invention is to provide a simple and economical method of manufacture of the propeller blades.

20 With the above and other objects in view the invention consists in the novel features of construction and the combination and arrangement of parts as will hereinafter more fully appear from the description and claims and the accompanying drawings, in which—

Fig. 1 is an elevation of a propeller constructed in accordance with this invention looking at the convex side of the blades.

Fig. 2 is an elevation similar to Fig. 1 looking at the concave side of the blades.

Fig. 3 is a section taken on line 3—3 on Fig. 1.

30 Fig. 4 is a section taken on line 4—4 on Fig. 1.

Fig. 5 is an enlarged elevation of one of the blades detached from the hub looking at the convex face thereof.

35 Fig. 6 is an elevation similar to Fig. 5 looking at the edge of the blade.

Fig. 7 is a section taken on line 7—7 on Fig. 5.

Fig. 8 is a section taken on line 8—8 on Fig. 5.

Fig. 9 is a section taken on line 9—9 on Fig. 5.

45 Fig. 10 is a fragmentary section of a portion of the blade root illustrating a modified form of groove for attaching purposes.

Fig. 11 is a fragmentary section of a portion of the blade root illustrating another modified form of groove for attaching purposes.

50 Fig. 12 is an elevation of the dies used for

stamping out a blade from a single blank of material.

Fig. 13 is a series of sections taken on lines A—B—C—D—E— and F on Fig. 12; and

Fig. 14 is a perspective of the dies separated and a blank of material from which a blade is pressed. 55

Like numerals of reference indicate like parts throughout the several figures, in which: 10 and 11 indicate dies for pressing a sheet of material 12 of uniform thickness to provide a blade with the proper concave and convex faces. At one end the sheet of material is formed in a cylinder or part cylinder 13 for attachment to the hub proper in such a manner that the blade may be rotated with respect to the hub and fastened at any of a variety of pitch angles. The cylinder or part cylinder 13 has a transverse groove 14 pressed therein that forms a circular rib on the inner face of the cylinder and is seated when in operative position in a groove formed in the hub proper. This is illustrated to an advantage in Fig. 3. A clamping ring 15 is placed in the grooved portion 14 of the cylindrical root portion 13 and a second band such as the flat band 16 may be placed about the portion 13 adjacent the ring 15 if so desired as an additional fastening means. In Figs. 10 and 11 modified forms of ring receiving 70 grooves 17 and 18 are shown. 75

After the blade is stamped or pressed from a flat sheet of material the forward or convex side is completely formed as to shape, angle and finish, except for polishing. The cross section of the blade is then brought to the form of a good airfoil by cutting the edges of the concave side off substantially straight across as at 19, Figs. 8 and 9, to provide flat 80 surfaces at the leading and trailing edges of the concaved driving face of the blade and disposed in the planes of the chords of the respective blade sections or elements. As clearly shown in Fig. 5, these surfaces 19 increase in width as they approach the tip or narrow end of the blade which increases in width from tip to root. This results from the fact that the camber of the blade attains its highest point or peak at approximately one-third of the chord or blade width back of the 85 90 95

leading edge and the resulting cross sections of the blade are of good aerofoil form from about 30 per cent of the radius to the tip of the propeller.

From the foregoing it will be seen that a metal propeller blade has been provided that is formed by pressing or stamping the same from a single blank of material in such manner as to necessitate only the cutting off of

10 the edges of the concave side and the polishing to produce the finished product. The blades thus formed can easily be made in quantity production at a minimum cost. The 15 cylindrical hub portion 13 allows for the ready attachment of the blade to the hub proper and for the rotation thereof with respect to the hub proper to obtain the desirable pitch angle in which position it may be secured by the securing bands.

20 The propeller or blade thereof, formed in accordance with the invention, has unique and important features. The fact that sheet material (metal or other suitable sheet material) and only a single sheet thereof, is used for the 25 formation of an aerodynamically efficient blade, is of particular interest not only from the standpoint of economy including manufacture (material, simplicity and ease of construction, time, etc.), but also from the stand- 30 point of the high ratio of strength per unit of weight. In connection with the matter of strength it should be noted that the invention provides a blade or a propeller having a high 35 factor of inherent rigidity due to the structural formation, tending to overcome deflecting forces which would in turn tend to de- 40 stroy or impair its aerodynamical and/or structural efficiency. Yet the blades are efficient and therefore effective for their pur- 45 poses because they are given a good aerofoil form. The curling inward of the edges of the blades as the edges approach the root or hub portion, whether the curling be extreme as illustrated as at 13 or less so as shown far- 50 ther out, gives increased strength as will be appreciated and may assist in the securing of the blade or blades to a hub or rotor member proper. The many other advantages of the invention should be apparent to those skilled 55 in the art.

Hence, while I have illustrated and de- 55 scribed what may be termed at present a preferred form of the invention, many changes may be made therein and the invention may 60 be embodied in many other forms bearing little resemblance in some respects to that illustrated, without departing from the spirit of the invention or the scope of the appended claims.

60 I claim:—

1. An aeronautical propeller blade having concavo-convex aerodynamically efficient blade sections each of which has the leading and trailing edges of its driving face flattened 65 in the plane of the chord of the sections.

2. An aeronautical propeller blade of pressed metal of uniform cross sectional thickness having concavo-convex aerodynamically efficient blade sections gradually increasing in width from root to tip of the blade 70 and having the leading and trailing edges of their respective driving faces flattened to provide smooth surfaces in the planes of the chords of the sections and decreasing in width from tip to root of the blade. 75

3. An aeronautical propeller blade of pressed metal of uniform cross sectional thickness and tapering in width from root to tip having concavo-convex aerodynamically efficient blade sections of substantially 80 the same negative camber on the driving face as positive camber on the back, the sides of the blade at the root being curled inwardly of the leading and trailing edges to provide a tubular root portion changing gradually 85 from a relatively small elliptical cross section at its inner end to a relatively large circular section at its outer end.

4. In a propeller, a cylindrical hub, a blade from root to tip of concavo-convex aerofoil 90 section having the sides thereof at the root of the blade elongated on arcuately converging lines forwardly of the concave face of the blade to provide a tubular root section of cylindrical cross-section embracing the said 95 hub and rotatable about the same, and means for securing said root section to the said hub.

5. In a propeller, a hub having a circumferential groove, a blade of concavo-convex aerofoil section having the sides thereof at 100 the root elongated on converging lines forwardly of the concave face of the section to provide a tubular root portion embracing the hub and conforming to the shape of the latter, each of said elongated sides having a rib 105 seating in the groove of the hub, and clamping means embracing the said hub and root portion.

6. In a propeller, a cylindrical hub having a circumferential groove, a blade of concavo-convex aerofoil section having the sides thereof at the root arcuately elongated on converging lines forwardly of the concave face of the section to provide a substantially cylindrical hub-encircling root portion, each of 110 said elongated sides having a portion thereof formed to present a groove in the outer face of the root portion and a rib on the inner face thereof, the said rib being seated in the groove of the hub, a clamping ring seated in the said 115 grooves of the root portion, and means for expanding and contracting the ring.

7. An aeronautical propeller blade completely formed from a single flat sheet of metal of uniform cross sectional thickness to 120 provide a root portion curved in the arc of a circle and a series of concavo-convex aerodynamically efficient blade elements decreasing in width from root to tip of the blade, and having substantially the same negative 125 camber. 130

camber on the driving face as positive camber on the back with the camber attaining its peak at approximately one-third of the chord of the blade width back of the leading edge, said blade elements having the leading and trailing edges of their concave sides flattened in the planes of the chords of the respective elements.

5 In testimony whereof I affix my signature.
